BOWLING ALLEY MASKING UNIT
OR THE LIKE

Robert I. Anderson, Grand Haven, and Bert Hoeker, Muskegon, Mich., assignors to The Brunswick-Balke-Collender Company, Chicago, Ill., a corporation of Delaware

Application June 2, 1948, Serial No. 146,734

Term of patent 14 years

(Cl. D34—5)

To all whom it may concern:

Be it known that we, Robert I. Anderson and Bert Hoeker, both citizens of the United States, residents, respectively, of Grand Haven, in the county of Ottawa, State of Michigan, and Muskegon, in the county of Muskegon, State of Michigan, have jointly invented a new, original, and ornamental Design for a Bowling Alley Masking Unit or the like, of which the following is a specification, reference being had to the accompanying drawings, forming a part thereof, in which:

Fig. 1 is a front elevational view of the bowling alley masking unit or the like, showing our new design;

Fig. 2 is a side elevational view thereof; and

Fig. 3 is a bottom view thereof.

The dominant features of our new design are shown in solid lines in the drawings.

We claim:

The ornamental design for a bowling alley masking unit or the like, substantially as shown and described.

ROBERT I. ANDERSON.
BERT HOEKER.
